United States Patent Office

Des. 188,604
Patented Aug. 16, 1960

188,604

BUREAU

John J. Lubberts and Lambert J. Mulder, Grand Rapids, Mich., assignors to Tomlinson of High Point, High Point, N.C., a corporation of North Carolina

Filed Oct. 1, 1959, Ser. No. 57,764

Term of patent 14 years

(Cl. D33—6)

The single figure of the drawing is a front perspective view of a bureau embodying our new design.

The side not shown is like the side shown while the back is conventionally plain.

We claim:

The ornamental design for a bureau, substantially as shown and described.
